UNITED STATES PATENT OFFICE.

ALEXANDER DICKEY, OF HONEYVILLE, UTAH.

END WRENCH.

Application filed November 1, 1924. Serial No. 747,294.

This invention relates to end wrenches and aims to provide novel means carried by an end wrench for supporting a bolt or the like, so that the wrench may be employed as 5 a device for positioning bolts in obstructed places.

An important object of the invention is to provide a device of this character wherein a bolt may be readily and easily secured 10 in position on the wrench, eliminating the use of clamping jaws or the like for clamping the bolt to the wrench.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed, may be made within the scope of what is claimed, without departing from the spirit of the invention.

Referring to the drawing:

Figure 1 is a side elevational view of a 25 wrench equipped with a securing device constructed in accordance with the invention.

Figure 2 is a plan view thereof.

Figure 3 is an enlarged detail view of one 30 end of the wrench.

Referring to the drawing in detail, the reference character 5 indicates the body portion of the wrench, which is formed with angularly disposed end portions 6 and 7 respectively, which end portions are cut away 35 as at 8 to provide wrenches.

As shown by the drawing, the angular end portion 6 is provided with a depressed portion 9 which is circular in formation and designed to accommodate the head of a bolt, 40 the bolt in the present showing being indicated by the reference character 10.

Secured to the under surface of the angu-

lar portion 6 of the wrench is a retaining member 11 which is constructed of spring steel material and secured by means of the 45 rivet 12. This member 11 has the end portion thereof that overlies the depression 9 cut away to provide fingers 13 connected at their inner ends by the straight wall 13', said fingers having their outer ends bent 50 downwardly as at 14 to allow the head of a bolt to be guided into the depressed portion 9.

In the use of the device, should it be desired to position a bolt, as for instance in 55 the securing of a crank casing, the bolts may be readily positioned under the retaining member 11, whereby a person using the wrench may reach under the crank case and readily place the bolts in the bolt openings 60 of a crank case.

After the bolt has been positioned and it is desired to secure the nut thereto, the wrench 8 on the opposite end of the body portion may be utilized for rotating the nut 65 to properly position the same.

I claim:

A wrench including a body portion, said wrench having a curved depressed portion, curved to conform to the curvature of the 70 head of a bolt, a retaining member secured to the body portion, said retaining member having fingers and having a substantially straight wall connecting the fingers, said depressed portion adapted to accommodate the 75 head of a bolt, and said fingers and straight wall adapted to contact with the side surfaces of the bolt adjacent to the head to hold the bolt and prevent turning thereof.

In testimony that I claim the foregoing 80 as my own, I have hereto affixed my signature.

ALEXANDER DICKEY.
